UNITED STATES PATENT OFFICE.

T. BRIGGS SMITH, OF MARIETTA, OHIO.

IMPROVED METALLIC BUNG.

Specification forming part of Letters Patent No. **24,827**, dated July 19, 1859.

To all whom it may concern:

Be it known that I, T. BRIGGS SMITH, of Marietta, in the State of Ohio, have invented a Metallic Screw-Bung for Casks or similar Wooden Vessels for Holding Liquids; and I do hereby declare that the following is a full and exact description thereof, reference being had to the accompanying drawings, and to the letters of reference marked thereon.

The nature of my invention consists in forming the bung or stopple of metal with a screw formed on the same, to be introduced into the cask or other vessel by forming a corresponding screw therein, or by forcing it in without the previous formation of a screw-thread.

To enable others skilled in the art to make and use my invention, I will proceed to describe its construction and operation.

Figure 1 is the top of the bung, with two holes, A A, for the wrench. Fig. 2 represents a vertical central section of the bung. Fig. 3 is a section of the bung-stave, showing the form of the bung-hole. Figs. 4 and 5 are perspective views of the bung.

B B represent the screw, which is made with a thin knife-like edge, with a flat or plane surface between the threads. The object of the thin thread is that it may be easily forced into the wood without a previously-formed screw to receive it.

D D is a projecting square shoulder, the object of which is to make the bung tight inde-

pendent of the screw by being forced down in the recess E E, Fig. 3, in the stave.

C is a slightly-raised semi-cylindrical elevation at one point between two of the threads, the object of which is to further insure the tightness of the bung by preventing liquid from entering at the bottom of the bung between the threads of the screw, and finding its way out unless the bung were screwed in very hard.

Fig. 3 is a section of the stave prepared to receive the bung. E E is a recess in the stave, made beveling, contracting gradually to the bottom, in which the lower edge of the shoulder D may bear, so as to better secure tightness. A strip of india-rubber or other cloth may be introduced, if required.

I do not claim a bung inserted and held by means of a screw; but

What I claim as my invention, and desire to secure by Letters Patent, is—

A metallic screw-bung for casks or other wooden vessels for holding liquids, with a knife-like thread, and an elevation at any point between the threads, and a shoulder on the bung let into the stave, substantially as and for the purposes specified.

T. BRIGGS SMITH.
